UNITED STATES PATENT OFFICE

2,253,776

DEEP WELL APPARATUS

Ray B. Gaunt, Kansas City, Mo.

Application November 7, 1938, Serial No. 239,237

14 Claims. (Cl. 103—219)

My invention relates to deep well apparatus and one object is to provide new and useful means of this character whereby a pump may be supported in operative position in a well in such manner that it may be lifted to the surface for cleaning or repairing without disturbing the supporting apparatus.

Another object is to provide means adapted to seal off the casing exteriorly of said supporting means and also exteriorly of the pump, so that the separate means usually employed to prevent gas from escaping to the surface between the casing and the pump may be dispensed with.

Other objects will hereinafter appear and in order that the invention may be fully understood, reference will now be had to the accompanying drawings, in which:

Fig. 1 is a broken longitudinal section of a casing with my apparatus positioned therein for supporting the pump, sealing off the casing exteriorly of the apparatus and also exteriorly of the pump.

Fig. 2 is a similar view to Fig. 1 with the pump removed.

Fig. 3 shows the position of the different parts of my apparatus when being lowered into the well casing, the lowering means being omitted.

Fig. 4 is a detail perspective view of a slotted tubular member upon which a series of expandable packer elements and expanding means therefor are assembled.

Fig. 5 is a detail perspective view of one of the expandable packer elements.

Fig. 6 is a detail perspective view of one of the wedges or expanders.

Fig. 7 is an enlarged perspective view of a barrel in which the slotted tubular member, shown by Fig. 4, is slidably mounted.

Fig. 8 is a detail perspective of a plurality of slips which assist in supporting the apparatus in the casing.

Fig. 9 is a detail perspective of a sleeve with a plurality of bow springs mounted thereon.

Fig. 10 is a broken side view partly in section of the pump.

Referring in detail to the different parts, 2 designates a barrel upon which a large number of other elements of the apparatus are assembled to coat therewith in supporting a pump in the well casing A.

When the apparatus is lowered into the well to the desired depth it is initially supported with a plurality of segmental slips 3, having serrated faces 4 for engagement with the well casing A when the slips 3 are forced outward by the

tapered intermediate portion 7 of barrel 2. Each slip-segment 3 is fixed to the upper end of a respective resilient arm 8, fixed at its lower end to a ring 9 loosely encircling the barrel 2.

Ring 9 rests upon the upper end of a sleeve 10 freely mounted upon the lower portion of barrel 2 to which it is connected by diametrically opposed studs 11 projecting from the barrel and extending through inverted L-slots 12 in the sleeve 10. The upper end of sleeve 10 is freely connected to the lower part of ring 9 with lugs 13 fixed to the sleeve and bent at their upper ends to enter a circumferential groove 14 in the ring. The sleeve 10 is provided with a plurality of equally spaced vertically disposed bow springs 15 secured at their lower ends to the sleeve and having their upper ends freely extending into grooves 15a in the upper portion of the sleeve, so that when the apparatus is being lowered into or lifted from the well said springs may expand or contract and thus accommodate themselves to any irregularities which may be present in the inner surface of the casing A.

The lower end of barrel 2 is provided with a collar 16 having a downward flaring mouth 17 to prevent couplings or other projections on pump 18 from catching on said collar or the lower end of barrel 2 while the pump is being pulled to the surface. The lower edge of mouth 17 is relatively sharp to cut off cement deposits or other obstructions on the inner surface of casing A, so they will not interfere with the downward movement of the apparatus while being lowered in the well.

Referring now more particularly to the principal supporting means of the apparatus when positioned in the well, 19 designates a tubular member, the lower part of which is slidably mounted within the upper portion of barrel 2. The protruding portion of the tubular member 19 is equipped with annular expandable packers 20, 21 and 22, and annular wedge members or expanders 23, 24 and 25, respectively, which latter are adapted to expand the former into frictional engagement with the well casing A to cooperate with slips 3 in supporting the apparatus, the pump 18 and a column of oil when pumped upward in the casing. Expansion of the packers also seals off the casing A so that gas cannot flow upward nor the pumped oil downward between the tubular member 19 and the casing.

The packers 20, 21 and 22 are in the form of thin bands consisting preferably of an alloy forming a relatively soft metal that may be expanded by the respective expanders. Each packer comprises a cylindrical upper portion 26 and a

tapered lower portion 27. The tapered lower portion of packers 28 and 21 rest in correspondingly shaped seats in the upper ends of the expanders 24 and 25, respectively, and the tapered portion of packer 22 is adapted to rest in a tapered seat 28 in the upper end of the barrel 2, as shown by Figs. 1 and 2. The lower portions 29 of the expanders are tapered to extend into and expand the cylindrical portions of the respective packers 28, 21 and 22 when the expanders are forced downward, as will hereinafter appear.

The expander 23 has a tapered seat 30 in its upper portion to receive the conical lower end 31 of the pump head 32 which supports the pump and coats with the seat 30 in preventing gas from escaping upward or the pumped oil from flowing downward between seat 30 and the conical end 31, which latter preferably consists of soft metal like the expandable packers.

The packers 28, 21 and 22 are slidably mounted upon the tubular member 19 and alternately arranged with the respective expanders 23, 24 and 25, all of which are likewise slidably mounted upon the tubular member, excepting the uppermost expander 23 which is threaded or otherwise suitably secured upon the upper end of said tubular member 19.

In practice the load on the tubular member 19 forces the same downward together with the expanders 23, 24 and 25 which are pushed down into the respective packers, thereby expanding the latter so firmly into frictional engagement with the casing A that it would be exceedingly difficult to simultaneously loosen them when lifting the apparatus to the surface preparatory to transferring it to another well, so I have arranged to loosen the packers in succession by lifting the expanders one by one beginning with the upper expander 23.

To accomplish the foregoing result the tubular member 19 is provided with an upper pair of slots 34, an intermediate pair of slots 36, and a lower pair of slots 38, while the expander 24 has a pair of studs 40 projecting into the slots 34, the expander 25 a pair of studs 42 projecting into the slots 36, and the upper portion of barrel 2 a pair of studs 44 projecting into the slots 38.

The slots of each pair are diametrically opposed and extend longitudinally of the tubular member 19, and as the ends of the intermediate slots 36 extend slightly beyond the adjacent ends of the companion slots the latter are arranged out of longitudinal alignment with the former, as shown by Fig. 4. The upper slots are relatively short, the intermediate slots 36 are longer, and the lower slots 38 are the longest. Hence when a hoist, not shown, is attached to the upper end of the tubular member 19 and operated to lift my apparatus from the well after removal of the pump said tubular member will move upward and first raise the upper expander 23 from the packer 28, after which the expanders 24 and 25 will be successively raised from the packers 21 and 22 through the intermediary of their respective studs 40, 42 and the lower ends of slots 34 and 36. Continued upward movement of the tubular member 19 carries the lower ends of slots 38 into engagement with the studs 44 and thus lifts the barrel 2. After the packers 28, 21 and 22 have been thus relieved of the weight of the rest of the apparatus they are readily moved upward with the expanders and the barrel. By successively disengaging the packers 28, 21 and 22 from the casing A and before starting barrel 2 upward, it is apparent that

less power and a lighter hoist may be used to pull the apparatus to the surface than if all the packers were released from the well casing at the same time.

In practice when the apparatus is to be lowered in a well the sleeve 18 and slips 3 are moved downward on barrel 2 until the sleeve rests upon collar 16 and the slips are positioned at the lower part of the tapered portion 7 of the barrel. Sleeve 18 is then secured in lowered position by turning it axially to the right (Fig. 3), to engage the upper horizontal portion of L slots 12 with studs 11.

The apparatus is then lowered in the well by lowering mechanism (not shown) attached to the upper part of the apparatus. On reaching the desired depth the lowering mechanism is turned axially to the right, Fig. 3, until studs 11 register with the vertical portions of L slots 12, whereupon all of the apparatus, excepting slips 3 and sleeve 18, is lowered until tapered portion 7 forces the slips 3 into such firm engagement with casing A, that said slips will support the apparatus. During the last-mentioned turning and lowering operations sleeve 18 is held stationary by the springs 15 frictionally engaging casing A.

After slips 3 have been forced into firm engagement with casing A by the tapered portion 7 of barrel 2 they check further downward movement of the barrel, but the tubular member 19 continues to descend until the expanders 23, 24 and 25 are seated in the respective packers 28, 21 and 22.

The lowering mechanism is then disengaged from the apparatus and removed from the well after which pump 18 is lowered until its tapered portion 31 is seated in the upper expander 23, as shown by Fig. 1. The weight of pump 18 forces the expanders 23, 24 and 25 down into the respective packers until the latter are expanded firmly into sealing engagement with the casing A so they will cooperate with slips 3 in supporting the pump and a column of oil when pumped upward in the well.

When it is desired to lift pump 18 to the surface for repairs, or cleaning, an upward pull on the pump rod 48 will carry coupling 48 against collar 50. The upward pull is continued until the pump is lifted to the surface.

When pump 18 is being either lowered or raised the soft conical end 31 of the pump head 32 is prevented from contacting casing A and thereby becoming damaged, by means of laterally projecting guide lugs 52 on the pump head 32. The upper portion of the pump has one or more outlet ports 54 for the free passage of the oil but being narrow will prevent any debris which might fall from the surface from entering the pump. The guide lugs 52 on the pump head and guide lugs 56 on a pump rod coupling coat with casing A in guiding the pump while being lowered into or raised from the well.

Should the well quit producing, my apparatus may be lifted to the surface if desired for transfer to another well. The lifting operation is accomplished with a suitable hoist, not shown, which is lowered into the well, after pump 18 has been removed, and engaged with the upper part of the apparatus. As the apparatus is started upward the expanders 23, 24 and 25 are successively lifted by the tubular member 19 out of the respective packers 28, 21 and 22. Thus the pressure of the packers against the well casing is reduced to such extent that they are readily moved upward with the expanders by the

tubular member, which latter also lifts the barrel 2. As the barrel moves upward it permits the slips 3 to spring inward out of engagement with the well casing so that they may be lifted along with sleeve 10 by the collar 16.

From the foregoing description taken in connection with the drawings, it is apparent that I have provided pump supporting and casing sealing apparatus that is well adapted for the purpose intended and while I have shown a preferred embodiment of said apparatus, I reserve all rights to such changes and modifications thereof as properly fall within the spirit and scope of the invention as claimed.

Having thus described my invention, what I claim and desire to secure by Letters Patent, is:

1. An apparatus of the character described comprising a barrel adapted to be lowered into a well casing, a member vertically slidably in said barrel and projecting from the upper portion thereof, means for limiting said slidable movement, a plurality of expansible packers freely mounted upon the projecting portion of said member, expanders slidably mounted upon the first-mentioned member and adapted to expand the respective packers into sealing engagement with the casing when the first-mentioned member is forced downward in the barrel, and means operably connecting said expanders to the first-mentioned member whereby when the latter is pulled upward the expanders will be successively disengaged from the packers.

2. An apparatus of the character described comprising a barrel adapted to be lowered into a well casing and provided at its upper end with a tapered seat, a tubular member slidably mounted in said barrel and projecting from the upper end thereof adapted to support a pump when the same is lowered into the casing, means for limiting the sliding movement of said tubular member, an expansible packer mounted upon the projecting portion of the tubular member and provided with a tapered end adapted to enter the tapered seat in the barrel, an expander freely mounted upon the tubular member and adapted to expand said packer into sealing engagement with the casing when the tubular member is forced downward by the weight of the pump, means for limiting the movement of said expander upon the tubular member, and means for supporting the barrel while the packer is being expanded into frictional engagement with the casing.

3. An apparatus of the character described comprising a barrel adapted to be lowered into a well casing, a tubular member slidably mounted in said barrel and projecting from the upper end thereof, means for limiting the sliding movement of said tubular member, a plurality of expansible packers freely mounted upon the projecting portion of the tubular member and the lowermost one of which is seated upon the upper end of the barrel, expanders mounted upon the tubular member and adapted to expand the respective packers into sealing engagement with the casing when the tubular member is forced downward by the weight of the pump, and means operably connecting said expanders to the first-mentioned member whereby when the latter is pulled upward the expanders will be successively disengaged from the packers.

4. An apparatus of the character described comprising a barrel adapted to be lowered into a well casing, a tubular member mounted in said barrel and projecting from the upper end thereof

adapted to support a pump when the same is lowered into the casing, stud and slot connections whereby said tubular member is connected to the barrel, an expansible packer freely mounted upon the projecting portion of the tubular member and adapted to seat upon the upper end of the barrel, an expander freely mounted upon the tubular member and adapted to expand said packer into sealing engagement with the casing when the tubular member is forced downward by the weight of the pump, stud and slot connections whereby said expander is slidably connected to the tubular member, and means for supporting the barrel while the packer is being expanded into frictional engagement with the casing.

5. An apparatus of the character described comprising a barrel adapted to be lowered into a well casing, a tubular member slidably mounted in the barrel and projecting from the upper portion thereof, said tubular member having a tapered seat at its upper end, a pump adapted to be lowered into the well and provided with a head having a tapered portion adapted to fit into and seal the seat in the upper end of the tubular member, means for limiting the sliding movement of said tubular member, an expansible packer freely mounted upon the projecting portion of the tubular member and adapted to seat upon the upper end of the barrel, an expander mounted upon the tubular member and adapted to expand said packer into sealing engagement with the casing when the tubular member is forced downward by the weight of the pump, and means for supporting the barrel while the packer is being expanded into frictional engagement with the casing.

6. An apparatus of the character described comprising a barrel adapted to be lowered into a well casing, a tubular member slidably mounted in the barrel and projecting from the upper portion of the barrel, said tubular member having its upper end tapered downwardly, means for limiting the sliding movement of said tubular member, an expansible packer freely mounted upon the projecting portion of the tubular member and adapted to seat upon the upper end of the barrel, an expander mounted upon the tubular member and adapted to expand said packer into sealing engagement with the casing when the tubular member is forced downward, means for supporting the barrel while the packer is being expanded into frictional engagement with the casing, a pump adapted to extend freely through the barrel and the tubular member, a head to said pump having a downward tapered portion to rest in the seat in the upper end of the tubular member and form therewith a gas-tight seal, and a rod extending upwardly through the pump and whereby the latter may be operated, or may be either lowered to working position or be lifted to the surface.

7. In an apparatus of the character described, means adapted to be lowered into a well casing, a tubular member slidably connected to said means, a plurality of expansible packers freely mounted upon the tubular member and the lowermost one of which is adapted to seat upon said means, expanders freely mounted upon the tubular member and alternately arranged with said packers and adapted to expand the same into sealing engagement with the casing, and means operably connecting said expanders to the tubular member whereby when the latter is pulled up-

ward the expanders will be successively disengaged from the packers.

8. In an apparatus of the character described, means adapted to be lowered into a well casing, a tubular member slidably connected to said means provided with longitudinal slots spaced one below the other and of increasing length from the uppermost slot to the lowermost slot, a plurality of expandable packers freely mounted upon the tubular member and the lowermost one of which is adapted to seat upon said means, expanders freely mounted upon the tubular member and alternately arranged with said packers and adapted to expand the same into sealing engagement with the casing, and elements extending from said expanders into the respective slots whereby said expanders are successively disengaged from the packers when the tubular member is pulled upward.

9. In an apparatus of the character described, a barrel adapted to be lowered into a well casing and provided at its upper end with a tapered seat, an expandible packer having a tapered portion resting in said seat, a tubular member freely mounted in the barrel and adapted to support a pump, means freely connecting said tubular member to the barrel, and an expander associated with the tubular member and adapted to force the expandible member into sealing engagement with the well casing.

10. In combination with a well casing and a pump, a barrel adapted to be lowered into the well casing and provided at its upper end with a seat, an expandible packer adapted to rest on said seat, an expander adapted to expand said packer into sealing engagement with the well casing, a tubular member adapted to support the pump and upon which said expander is mounted, and pin-and-slot connections freely connecting said tubular member to the barrel.

11. In apparatus of the character described, a barrel adapted to be lowered into a well casing, a member associated with said barrel, studs and slots connecting the member to the barrel to permit independent longitudinal movement of said member, an expandible packer freely associated with said member and the barrel, and an expander controlled by the member and adapted

to expand the packer into sealing engagement with the well casing.

12. In combination with a well casing, a barrel provided at its upper end with a tapered seat and adapted to be lowered into a well casing, a member associated with said barrel, means loosely connecting the member to the barrel to permit limited independent longitudinal movement of said member, an annular expandible member freely mounted upon said member and having a tapered portion for entering the tapered seat of the barrel, and an annular expander controlled by the member and adapted to expand the packer into sealing engagement with the well casing and the tapered seat of the barrel.

13. In combination with a well casing, a barrel adapted to be lowered into said well casing, a member associated with said barrel, means loosely connecting the member to the barrel to permit limited independent longitudinal movement of said member, an expandible packer mounted upon said member and adapted to be seated upon the barrel, an expander freely mounted upon the member and adapted to expand the packer into sealing engagement with the well casing and the barrel, and studs and slots connecting the expander to the member to permit limited independent movement between said expander and the member.

14. In combination with a well casing, a barrel adapted to be lowered into said casing, means adapted to be forced into engagement with the casing by said barrel to support the latter, a tubular member associated with the barrel and adapted to support a pump, means loosely connecting the tubular member to the barrel to allow limited independent movement of said tubular member, an expandible packer freely associated with the tubular member and adapted to rest upon the barrel, an expander loosely mounted upon the tubular member and adapted to expand the packer into sealing engagement with the casing and the barrel, and means loosely connecting said expander to the tubular member to permit limited independent movement of the latter.

RAY B. GAUNT.
